ATTORNEY.

UNITED STATES PATENT OFFICE.

EDWIN MILLER, OF HARTFORD, CONNECTICUT.

ELECTRIC SADIRON.

1,351,054.

Specification of Letters Patent. Patented Aug. 31, 1920.

Application filed January 19, 1920. Serial No. 352,467.

To all whom it may concern:

Be it known that I, EDWIN MILLER, a citizen of the United States, residing at Hartford, in the county of Hartford and 5 State of Connecticut, have invented certain new and useful Improvements in Electric Sadirons, of which the following is a specification.

This invention relates to electric sad 10 irons. An electric sad iron as is known, comprises a body and a handle, the body usually inclosing a rheostat to which current is supplied from a lead or cord associated with an electric connection of some 15 suitable character usually on the body. The principal object of the invention is the provision of simple means by which such a cord from a plug or something of a similar nature, can be led to a connection on the iron 20 and held in proper relation therewith during the manipulation of the iron the wire being supported in such a way that it will not foul and at the same time the handle is not perforated and thus weakened. I 25 provide an article in the nature of an attachment which is capable of inexpensive construction and which will efficiently and satisfactorily support a wire lead or cord in such way that current may be conducted to 30 the rheostat or equivalent heater in the body of the iron.

In the drawings accompanying and forming part of the present specification I have shown one of the several forms of embodiment of the invention which to enable those skilled in the art to practise the same will be set forth fully in the following description. I am not restricted to this disclosure. I may depart therefrom in several respects 35 40 within the scope of the invention defined by the claim following said description.

Referring to said drawings:

Figure 1 is a side elevation of an iron involving the invention.

Fig. 2 is a front view of the same.

Like characters refer to like parts in both views.

The iron is denoted in a general way by 2 its body inclosing a rheostat or like heater, 50 to which current is supplied by a cord as 3 the lower end of the cord extending into the insulated socket piece 4. The handle of the iron is designated by 5 and it is solid and

may be of wood, composition or other suitable material. The ends of the handle are 55 connected as by screws as 6 and 7 to the upwardly-extending branches of the yoke 8 attached as by screws 9 to the upper side of the body of the iron.

When the current is "on," the body of the 60 iron is heated as will be understood and the current may be turned on or off through a switch of some suitable character which I have not deemed it necessary to show.

There is a suitable support as 10 which, 65 with its various portions may be conveniently made in one piece from wire. This cord support 10 comprises an elongated body 11 furnished with suitable means by which it may be connected to the iron in a substantial and secure manner. For this purpose the body or shank 11 is furnished for instance at its lower end with an eye or loop 12 to receive the forward screw 6 and thus bind the eye firmly against the front 70 part of the yoke 8, and as a consequence substantially maintain the shank of shaft 11 in an upright position. As shown the upper end of the shank 11 has a coiled head 12' 75 through which the cord 3 is adapted to extend.

It will be assumed that it is desired to introduce the wire or cord 3 into the head 12. In this case the following procedure 80 may be adopted: From below, the cord 3 will be inserted between first and second whirls of the coiled head and then bent around the upper side of the front whirl and carried under the free end of the front 85 whirl, the wire or cord at the same time slipping into the innermost whirl of the head.

It will be evident that the wire support used in connection with the iron is of exceedingly simple and inexpensive construction, it is light and possesses the requisite and necessary strength and effectually prevents the supply wire from fouling the iron. At the same time the strength of the handle 90 95 100 105 5 is in no sense affected because it is solid having no opening through it, which would naturally tend to weaken its strength.

What I claim is:

An article of manufacture for use in connection with an electric sad iron and to function as a wire support, comprising an elong-

gated shank having an eye at one end, to receive a screw by which it may be attached to the iron, and also having at the other end a plurality of coils into which the supply 5 wire of the iron may be threaded, the coils being adapted to surround and support said supply wire.

In testimony whereof I affix my signature in the presence of two witnesses.

EDWIN MILLER.
